UNITED STATES PATENT OFFICE.

DANIEL K. POMEROY, OF OTTAWA, ONTARIO, CANADA.

CHURN.

SPECIFICATION forming part of Letters Patent No. 271,266, dated January 30, 1883.

Application filed May 18, 1882. (Model.)

To all whom it may concern:

Be it known that I, DANIEL K. POMEROY, of Ottawa, in Province of Ontario and Dominion of Canada, have invented certain Im-
5 provements in Churns, of which the following is a specification.

My invention relates to oscillating churns; and it consists in a novel manner of constructing, hanging, and operating the same, as hereinafter fully set forth.

In the accompanying drawings, Figure 1 represents a perspective view, and Fig. 2 a vertical longitudinal central section, of the churn.

The objects of my invention are to render the operation of the churn easier than under former constructions, to cause the body to hang naturally in a horizontal position instead of tipping, and to produce a motion which shall cause the butter particles to be readily separated from the cream or milk. To this end I construct my churn as shown in the accompanying drawings, in which—

A represents a stout frame, consisting of uprights *a*, inclined braces *b*, and cross ties or braces *c*, which may be put together in any approved manner, but preferably arranged as shown.

B represents a rock-shaft, journaled in the upper ends of the uprights *a*, and C the churn body or vessel suspended from the rock-shaft B by links or rods D passing through said rock-shaft and bent at their lower ends to form journals *d*, which pass through ears *e* formed by the projection above the body of bars *f* secured to the sides thereof. By this arrangement of parts it will be seen the body is free to swing back and forth, with the rock-shaft B as a center of motion, and also to rock or tip upon the joints or journals *f*, thereby securing 40 a compound motion. By thus passing the rods through the rock-shaft, instead of forming a joint and employing a stationary cross-bar, I avoid any side play of the churn-body.

For the purpose of imparting to the churn the compound motion noted I provide the frame with arms or brackets E, secured firmly to the uprights *a*, and carrying a crank-shaft, F, the cranked portion of which is carried through ears or boxes *g* at the upper side of the body 50 and near the end thereof, and one end of which is furnished with a hand crank or winch, G, as shown. The rotation of the crank-shaft pro-

duces both a rocking and a swinging motion of the body, which body is of the form and construction shown in Fig. 2. By referring to said figure the body will be seen to consist of vertical sides *h*, a flat bottom, *i*, and rounded ends formed by a series of flat-faced strips, *j*, meeting each other at a slight angle. The top is formed with an opening, *k*, closed by a cover, 60 *H*, and at each side of the opening there is placed an inclined board or deflector, *l*, which serves to direct the cream downward away from the opening. The cream is caused by the operation of the churn to travel along the bottom of the body, follow the contour of the end, and thereby pass to the top of the body, and thence to be thrown by the deflector down to the bottom again, when the travel is repeated but in a reverse direction. In traveling over the successive flat faces of the ends the body is broken up and caused to roll over and over—a result which is found in practice to be highly conducive to a rapid separation of the butter particles.

I am aware that churn-bodies have been provided with rounded ends and also with square ends, and that such bodies have been suspended by rods or bars and given a compound motion by the rotation of a crank-shaft; but so far as I am aware no one has ever before located the joints or journals by which the body is attached to the links above the body, so that the tendency of the body under all circumstances is to hang down below said pivots or journals in a horizontal position, even in case the crank-shaft becomes disconnected from the body. The motion secured is also different from that produced by arranging the pivots below the top of the body, as under my arrangement the body is moved endwise in rocking or tipping upon the pivots, and under the other arrangement mentioned it simply rocks without moving endwise. The difference is found in practice to be very considerable, as it insures a more certain travel of the cream upward around the ends. The operation of the churn under this arrangement is also much easier than under the former plan, since the tendency to assume a horizontal position causes the body to raise or assist in raising itself at the end of its movement in either direction.

Having thus described my invention, what I claim is—

1. The herein-described churn, consisting of frame A, body C, suspended by links or rods D, pivoted to ears projecting above the body, as shown and described, and crank-shaft F, journaled in the frame and connected with the body, said parts being combined and arranged to operate substantially as set forth.

2. In combination with frame A, constructed substantially as described, rock-shaft B, jour-

naled in said frame, rods D, passing through to said rock-shaft, and the body C, provided with ears projecting above the body and jointed to the rods D, all as shown and described.

DANIEL K. POMEROY.
